UNITED STATES PATENT OFFICE.

DOUGLAS F. ARNOT, OF ORANGE, MASSACHUSETTS.

ROTARY ENGINE.

1,263,993.

Specification of Letters Patent. Patented Apr. 23, 1918.

Application filed August 21, 1916. Serial No. 116,113.

To all whom it may concern:

Be it known that I, DOUGLAS F. ARNOT, a citizen of the United States, residing at Orange, in the county of Franklin and State 5 of Massachusetts, have invented certain new and useful Improvements in Rotary Engines, of which the following is a specification.

This invention has relation to fluid pressure engines of the rotary type, and the nature and objects thereof will be readily apparent to those skilled in the art to which it appertains, in the light of the following explanation of the accompanying drawings, 15 illustrating what I now believe to be the preferred embodiment or mechanical expression, of my invention from among other forms and arrangements within the spirit thereof or the scope of the appended claim. 20 However, an object of the invention is to provide a rotary engine particularly adapted for marine use, and to that end embodies a new and novel fluid pressure controlling valve, whereby the direction of rotation of 25 the rotor may be quickly reversed or the engine completely stopped.

Another object of the invention is to provide a rotary engine in which the rotor is mounted concentrically within the casing, 30 and in which the inner wall of the cylinder is so formed adjacent the point of pressure inlet so as to permit the pressure to exert an initial impulse against the abutment whereby an increase of power is obtained in 35 this engine, over others of a similar type.

In addition to the foregoing, by invention comprehends improvements in the details of construction and arrangement of parts to be hereinafter more fully described and particularly pointed out in the appended claim. 40

In the accompanying drawings in which similar and corresponding parts are designated by the same characters of reference throughout the several views in which they 45 appear:

Figure 1, is a view in vertical section with parts in elevation of a rotary engine constructed after the manner of my invention.

Fig. 2, is a view thereof in end elevation with parts broken away.

Fig. 3, is a detail transverse section taken through the valve.

With reference to the drawings, 1 indicates a cylindrical casing, closed at either end by means of removable end plates 2. 55 Each plate 2 is provided with a transverse central opening, in alignment, providing bearings for a power shaft 3 which extends through the casing.

A rotor 4 is mounted concentrically upon 60 the shaft 3, and is provided at uniformly spaced intervals about its circumference, with radially and inwardly extending recesses 5 for the reception of sliding abutments 6. A coil spring or the like 7 is disposed between the under side of each abutment, and within the recesses 5 and is adapted to bear against the bottom of said recesses to normally hold the abutment outward. The interior wall of the casing is 70 formed for one-half its circumference viz—the upper portion thereof, concentrically with the axis of the shaft 3, while the remainder of the wall is formed along the lines of a compound curve, the lower portion 75 of the inner wall of the casing being disposed concentrically to the surface of the rotor, very closely spaced therefrom for a short distance to each side of the vertical center of the casing. On Fig. 1 of the 80 drawings this curvature of the wall extends from *a* to *b*. From the point *b* the inner wall of the casing is formed into a rapid curve coinciding with the concentric wall of the casing at the horizontal center of the 85 casing indicated at *c*, while the left side of the casing is formed symmetrically with relation to the right side, the wall of the casing curving rapidly from the point *a* to the point *d*. 90

The casing is rested upon one side in a base portion 8, having lower attaching flanges 9. The base portion is further provided with an elongated cylindrical opening 10 which extends substantially tangential 95 to the casing 1, and the rear end of said opening 10 is in communication with a fluid pressure supply pipe 11 which is threadedly engaged in an enlargement 12 at the rear end of the base portion. The casing and 100 base portion are further provided with ports 13 and 14, located at the left and right sides respectively of the vertical center of the casing, the inner ends of said ports entering

the cylinder adjacent the points *a* and *b* respectively. The lower ends of the ports are adapted to enter the opening 10. A tubular valve 15 is inserted in the opening, said 5 tubular valve being provided with a pair of openings 16 and 17 located in its side walls and suitably spaced longitudinally of the valve so as to register with the ports 13 and 14 successively in different rotative positions of the valve. The rear end of the valve is open and is adapted to register with the supply 11, while the forward end of the valve is closed as at 18. A plate 19 is bolted to the forward end of the base, by means 10 of bolts 20, whereby the valve is retained in its opening. The plate 19 is formed with an opening provided with a packing gland 21 through which a valve stem 22 passes, said valve stem 22 having threaded engagement with the closed end 18 of the valve. A circle is inscribed concentrically about the valve 22 upon the plate 19, and certain indications are marked upon the circles to which reference is had by means of a pointer 15 23 mounted upon the valve 22, for rotation therewith. A wheel 24 serving as a handle for the valve stem 22 is provided whereby said valve stem may be rotated.

With the valve disposed in the position 20 shown in Fig. 1, the opening 16 therefrom and the ports 13 are in registration whereby fluid pressure entering the valve through pipe 11 may enter the channel in the casing around the rotor 4, thereby initiating 25 rotative movement of the rotor. The position of the valve is indicated by the location of the pointer 23, with reference to one of the inscribed marks upon the face plate 19. If the rotor is to be reversed, the 30 handle 24 is rotated so as to bring its pointer 23 into a position diametrically opposite its former position, whereupon the valve opening 17 will be brought into registration with the port 14 and the fluid pressure permitted to enter the casing at the 35 right hand side thereof.

If the engine is to be stopped, the valve is rotated so as to dispose neither of its 40 ports in registration with the aforesaid ports 13 and 14 whereupon the fluid pressure is cut off. This position of the valve is arrived at when the pointer 23 is disposed vertically.

It is to be observed in connection with 45 the entrance of the fluid into the casing, that the radial movement of the abutment after the same has passed one of the ports 13 or 14 will be relatively rapid, thus imparting an initial strong impulse to the rotor. The 50 inward movement of the abutment from the point *c* to *b* to exhaust the spent fluid is very rapid, as is also the outward movement of the abutment after receiving an impulse from the point *a* to *d*.

Owing to the provision of the valve 15, 65 this engine is especially applicable to marine use, as the boat propelling mechanism may be quickly reversed.

Coincidentally with the admission of fluid pressure through either of the ports 13 and 70 14, the establishment of an exhaust port is automatically taken care of in the following manner: At diametrically opposite points of the ports 16 and 17 of the cylinder valve, there are located cavities 13^a and 75 14^a respectively. These cavities are on the exterior of the cylinder and have no communication with the interior thereof. They are however, connected by means of a spiral groove 18^a; with reference to Fig. 3 of the 80 drawings it will be noted that the said groove extends substantially one-half the circumference of the valve, and at diametrically opposite points in the valve seat, there is provided oppositely extending exhaust 85 ports 18^b and 18^c adapted for successive communication with the spiral groove 18^a in different positions of the valve. Thus, upon reference to Fig. 1, it will be noted that the port 14 is employed as an exhaust 90 port, the spent fluid entering thereto from the cylinder, into the cavity 14^a, along the spiral groove 18^a to the exhaust port 18^c. If the valve is turned in an opposite direction 95 so as to bring the cavity 13^a into registration with the port 13 so as to employ said port as an exhaust port, the spent fluid pressure will enter the cavity 13^a along the grooves 18^a and issue from the exhaust port 18^b. Thus it will be seen, either port 13 or 100 14 may be used interchangeably as an inlet and exhaust port. A second exhaust port may also be provided at the upper portion 105 of the engine casing as indicated at 25 to exhaust most of the fluid, and relieve the 110 pressure, the balance of the spent pressure and including the water of condensation being passed through either of the ports 13 and 14 in the manner above set forth.

While I have illustrated and described 110 my invention with some degree of particularity, I realize that in practice various alterations thereover may be made, and I therefore reserve the right and privilege of changing the form of the details of construction, or otherwise altering the arrangement of the co-related parts, without departing from the spirit of the invention or the scope of the appended claim.

Having thus described my invention what 120 I claim as new and desire to secure by Letters Patent is:

In a rotary engine, a casing having a pair 125 of parallel intake ports, a valve chamber in communication with said ports, a steam supply port at one end of the valve chamber and a pair of exhaust ports leading from said valve chamber at opposite sides between

the intake ports, a tubular valve fitting the valve chamber with one end opening into the steam supply port, and having a pair of longitudinally spaced ports at opposite sides for alternate registration with the intake ports, and a spiral cavity for communication at its intermediate portion with either of the exhaust ports and at its ends

with either of the intake ports, and means for rotating the valve.

In testimony whereof I affix my signature in presence of two witnesses.

DOUGLAS F. ARNOT.
